UNITED STATES PATENT OFFICE

161,190

TETHERED BALL GAME DEVICE

Sandy Lang, Chicago, Ill.

Application December 17, 1949, Serial No. 6,690

Term of patent 14 years

(Cl. D34—15)

To all whom it may concern:

Be it known that I, Sandy Lang, a citizen of the United States of America, residing at 6907 South Perry Avenue, Chicago, Illinois, have invented a new, original, and ornamental Design for a Tethered Ball Game Device, of which the following is a specification, reference being made to the accompanying drawing, forming part hereof.

Referring to the drawing, Fig. 1 is a side elevational view of a tethered ball game device embodying my new design; Fig. 2 is a rear end elevational view; Fig. 3 is a top plan view and Fig. 4 is a bottom plan view of the same.

I claim:

The ornamental design for a tethered ball game device, substantially as shown.

SANDY LANG.
